UNITED STATES PATENT OFFICE.

EDWARD S. HALSEY, OF LYNN, MASSACHUSETTS.

THERMOSTAT.

1,073,899.

Specification of Letters Patent. Patented Sept. 23, 1913.

Application filed December 1, 1911. Serial No. 663,448.

To all whom it may concern:

Be it known that I, EDWARD S. HALSEY, of Lynn, in the county of Essex and State of Massachusetts, have invented certain new and useful Improvements in Thermostats, of which the following is a specification.

The nature of my present invention is a volatile liquid thermostat, being an improvement in the class of thermostats described in my Patent No. 916,861, of March 30th, 1909, and my later applications, Serial Numbers 507,070, 507,071, 507,072 and 507,073.

The object of my present invention is to increase the sensibility, smooth and uniform travel of the diaphragm and to simplify manufacture.

Referring to the drawings which illustrate my invention, similar numerals and letters refer to similar parts throughout the several views, of which,

Figure 1 is a vertical cross section and Fig. 2 is a plan view of my thermostat.

It will be observed that the thermostat consists of two dished flanged corrugated metal disks F and D. D, the concave disk, forms the flexible diaphragm, pressed from thin tinned sheet steel which corresponds in form to the thicker and rigid front plate, F. The diaphragm plate is inserted within the flange of and against the front plate, and soldered about the periphery, thus forming a hermetically sealed expansion chamber entirely of steel or iron, the interior surface of which may be either tinned or bare. The only other metal exposed to the interior is the solder of the joint.

The flange rim carries a three-legged spider 1, with supporting legs at the extremities. This spider or cross frame is slotted at the center for a bell crank 2, having a backwardly extending lever 4, while the other arm of said bell crank carries a large anti-friction roller 5, engaging the stiffening plate 6, soldered to the center of the diaphragm.

A small and definite quantity of a suitable liquid L having its boiling point under atmospheric pressure at approximately 66 degrees Fahrenheit, is sealed between the diaphragm and front plate, being just sufficient in quantity to distend the diaphragm to its safe limit of travel when said liquid is fully volatilized. When the liquid is condensed

the flexible diaphragm collapses snugly against the front plate F, leaving a thin film of liquid between, all air being carefully excluded. When in this position the extension lever 4 is lowered so as to open the heat dominating valve to which it may be connected by means of a tension ligament secured by an eye 10 at the extremity of the lever. As soon as the temperature of the room, to the wall of which the thermostat is fixed, exceeds the boiling point of the liquid, the diaphragm is gradually distended, the lever and connecting ligament are raised, and the position of the connected heat dominating valve and consequently the temperature of the room are modified. The outward travel of the diaphragm is limited by the cross frame. The position of the diaphragm shown by solid lines in Fig. 1 is an intermediate position, and from this figure it will be observed that the diaphragm is so constructed, or formed by the shaping dies, as to give the annular portion between the periphery and the center plate a backward bend or bulge, whereby the lateral stress of the diaphragm in passing over center from the front position to the back position is relieved. Preferably the front plate is also given a similar, but slighter backward bow to support the bulged part of the diaphragm against atmospheric pressure in its innermost position when cooled. Such front plate, however, may be straight, as the permanent spring form originally given to the diaphragm at the part 3—3, will tend to arch it backward under the initial internal pressure.

Formerly it has been customary in constructing volatile liquid thermostats to introduce an excess of the volatile liquid, to insure volatilization of a sufficient quantity of the liquid to do the required work at the desired temperature, and for other reasons. But so far as I am aware, no permanent, volatile liquid thermostat has yet been produced, which is operative at or close to the vital room temperature of 70 degrees F., without complicated artificial means for subjecting the contents of the expansion chamber to considerably increased or diminished pressure from that of the atmosphere to modify the boiling points of the liquids respectively employed. Most commonly others have employed conglomerate mix-

tures with no stable boiling point, and which begins volatilization some 12 to 15 degrees below 70 F.

After years of research I have discovered that ethylamin, carefully refined and all moisture extracted, intermixed with a small quantity of refined spirits of ether sufficient to raise its boiling point to about 66 or 67 degrees F., and used in a steel or iron expansion chamber, sealed by common solder with the least possible amount of soldering flux, eminently answers my requirements. This substance causes volatile expansion of the diaphragm against atmospheric pressure 10 to commence at 66 or 67 degrees F., and forces the diaphragm under the increased tension of its own elasticity to the limits of its working travel at a temperature of about 72 degrees F., at which point volatilization 15 is complete. This brings the intermediate and most active movement of the diaphragm between the range of 68 and 72 degrees, within which range any heat dominating valve which may be geared thereto is under 20 constant control and adapted to occupy various positions corresponding to the conditions of the diaphragm to deliver the desired house temperature of 70 to 72 degrees. I have also discovered that nitrous ether 25 carefully refined, neutralized and concentrated just prior to its introduction in the steel expansion chamber, intermixed with sufficient refined common fluid ether to raise its boiling point to at least 66 degrees F., approximately, will also answer the purpose and be permanent if all precautions here enumerated are taken. The chamber should be soldered with a minimum quantity 30 of resin flux in preference to chlorid of zinc or soldering pastes, and pulverized quicklime should be introduced with the liquid partly to keep it neutral and partly to form an adhering granular deposit 35 on the inner walls of the chamber to facilitate volatilization, condensation and the capillary retention or wetting of the walls of the chamber.

I have found that of materials which 40 may be used, high grade tin plate most satisfactorily answers the requirements of the diaphragm, and that its thickness should be preferably about nine thousandths of an inch. I have also found that none of the 45 more common metals except iron or steel, or in other words, the ferrous materials, can be used successfully with either of the liquids mentioned, because the liquids attack and decompose the other common metals, such as copper and brass. It is not to be 50 understood that ferrous materials are the only ones which can resist the chemical action of the liquids, for nickel, among others, is also unaffected, but owing to relative 55 costs, the ferrous metals are the only commercially practicable ones.

I claim—

1. A thermostatic motor consisting of a chamber having oppositely arranged walls, one of which walls is movable toward and from the other, and in the normal contracted condition of the motor is close to said other wall, a working fluid which at atmospheric pressure is entirely liquid at 66° Fahrenheit, completely filling the space between said walls in the contracted condition of the motor, said fluid being completely gaseous under atmospheric pressure at a temperature of approximately 73° Fahrenheit. 70 75

2. A thermostatic motor, consisting of a hermetically sealed expansion chamber having a movable wall, of which the expanding movement is resisted only by atmospheric pressure and the necessary opposition of the thing on which it acts, and a volatile liquid within the chamber, having a boiling point under such resistance, of approximately 67 degrees F. 80 85

3. A thermostatic motor consisting of a chamber containing a quantity of volatile liquid and having a wall arranged to move under pressure generated by volatilization of the liquid, the pressure resisting such motion of said wall being only that caused by atmospheric pressure and by the opposition of the actuated mechanism or device, and the liquid having a boiling point under such pressure between 66° and 73° F., and being completely volatilized at 73° F. 90 95

4. A thermostatic motor, consisting of a hermetically sealed expansion chamber having a movable wall, of which the expanding movement is resisted only by atmospheric pressure and the necessary opposition of the thing on which it acts, and a small quantity 100 of a compound volatile liquid essentially ethylamin within said expansion chamber. 105

5. A thermostatic motor, consisting of a hermetically sealed expansion chamber having a movable wall, of which the expanding movement is resisted only by atmospheric pressure and the necessary opposition of the thing on which it acts, and a small quantity 110 of a compound volatile liquid essentially nitrous ether within said expansion chamber. 115

6. In a volatile liquid thermostat, a hermetically sealed expansion chamber, and an actuating volatile liquid contained therein, and having a boiling point at atmospheric 120 pressure of approximately 67 degrees Fahrenheit; such liquid being essentially, ethylamin, or nitrous ether, or a mixture of either ethylamin or nitrous ether with common liquid ether. 125

7. In a volatile liquid thermostat a hermetically sealed ferrous metal expansion chamber, and an actuating volatile liquid within said chamber consisting essentially of ethylamin. 130

8. In a volatile liquid thermostat a hermetically sealed elastic ferrous metal expansion chamber, and an actuating volatile liquid within said chamber consisting essentially of nitrous ether.
9. In a volatile liquid thermostat a hermetically sealed elastic ferrous metal expansion chamber, and an actuating volatile liquid within said chamber consisting essentially of ethylamin intermixed with a small quantity of common liquid ether.
10. In a volatile liquid thermostat a hermetically sealed elastic ferrous metal expansion chamber, and an actuating liquid within said chamber consisting essentially of nitrous ether intermixed with a small quantity of common ether.
11. In a volatile liquid thermostat a hermetically sealed metallic expansion chamber; a suitable volatilizing actuating liquid within said chamber, and a suitable powdered material adherent in fine particles to the interior walls of said chamber for the purposes specified.
12. In a volatile liquid thermostat a sealed metallic expansion chamber and a volatile actuating liquid consisting essentially of nitrous ether in said chamber, with a quantity of a suitable alkaline material such as powdered lime, for the purposes specified.
13. In a volatile liquid thermostat a sealed metallic expansion chamber consisting of an outwardly dished front plate F, and a flexible corrugated lever-actuating diaphragm D, united peripherally and providing a peripheral stiffening rim; the plate F having a portion between its center and periphery which is straight or slightly concaved toward said diaphragm, and the latter being correspondingly formed to normally lie snugly against F, but having a backwardly bulged annular spring portion near its periphery at 3—3 to ease the trav- erse strain of the diaphragm in passing mid position.
14. In a volatile liquid thermostat a sealed metallic expansion chamber having a movable wall which consists of a corrugated double throw diaphragm so formed that its radial lines from periphery to center plate bow backward throughout its travel for the purpose specified.
15. A volatile liquid thermostat comprising a hermetically sealed chamber having opposed walls, one of which is elastically movable toward and from the other under conditions respectively in which said thermostat is collapsed and expanded, and a working fluid contained in said chamber having extreme range of temperature from complete liquefaction to complete volatilization, at atmospheric pressure of approximately six degrees Fahrenheit.
16. A thermostat comprising an expansion chamber composed of steel or iron walls, one of which is flexible and movable toward and from the other, the joints of such walls being sealed with solder, and a quantity of ethylamin refined and free from moisture, contained in said chamber and having a boiling point at atmospheric pressure at about 67 degrees Fahrenheit.
17. A thermostat comprising an iron or steel expansion chamber having a flexible wall, and a quantity of nitrous ether, refined, neutralized and concentrated, contained in said chamber and mixed with refined common fluid ether in proportions sufficient to bring the boiling point of the mixture to approximately 67 degrees Fahrenheit.
